UNITED STATES PATENT OFFICE

LOUISE GASTON, OF CHICAGO, ILLINOIS

WREATH

Application filed March 21, 1927. Serial No. 176,951.

My present invention pertains to imitation wreaths and more particularly to an illuminated imitation holly wreath.

I have found that there is considerable demand for imitation wreaths, particularly the illuminated type. The natural holly wreaths are not always satisfactory for the reason that they are often difficult to illuminate and can only be used for one season.

10 I propose to provide an ornament of pleasing appearance, capable of being illuminated with facility and adapted to be hung in the window in place of holly wreaths during the Christmas season. Obviously the invention 15 may be embodied in a wreath or the like of any suitable character.

Other objects and advantages of my invention will more fully appear from the following detailed description taken in connection 20 with the accompanying drawing which illustrates several embodiments thereof, and in which

Fig. 1 is an elevation partly in section of a wreath in accordance with the features of 25 the present invention, showing it with one of its sides partially removed;

Fig. 2 is a fragmentary sectional view taken on substantially the line 2—2 of Fig. 1 looking in the direction indicated by the arrows;

Fig. 3 is a fragmentary view, partly in section, illustrating a modification of the invention; and

Fig. 4 is a fragmentary sectional view taken on substantially the line 4—4 of Fig. 3 looking in the direction indicated by the arrows.

Referring now to the drawing in detail, in which like reference numerals designate similar parts throughout the several views, 40 10—10 designates the sides of my novel imitation holly wreath. Each of the sides 10 comprises a layer of paper or cardboard 11 or other translucent material having its 45 outer surface ornamented to simulate a holly wreath, as is clearly shown in Fig. 1. The ornamentation may be placed on the layer 11 by printing, painting, or any other suitable process. Each side also includes a layer 50 of celluloid or other substantially transparent

material 12 which may be glued or otherwise secured directly to the outer surface of the layer 11. Obviously the ornamental pattern may be put on the back of the transparent sheet if desired. The edge of each side 55 is cut to show the profile of the wreath, as is shown at 13 in Fig. 1, to cause the sides to more nearly simulate a wreath.

Each side 10 has a substantially central opening 14 which communicates with the opening in a tubular element or sleeve 15 which may be made of cardboard or any other suitable material. The sleeve 15 is disposed in coaxial alignment with the openings 14 and is located between the two sides 10. 65 Furthermore, the sleeve or collar 15 is flanged at 16—16 and the inner surfaces of the sides 10—10 are glued or otherwise suitably secured to the flanges 16—16 about the openings 14. 70

It will be observed from Fig. 2 that the sides 10—10 converge or, rather, are bent toward each other at their outer peripheries. The central portions of the two sides 10—10 are spaced from each other by means of the 75 connecting collar or sleeve 15. The sleeve 15 may, if it is so desired, also be made of transparent material. It may, if desired, bear a part of the ornamentation to make the illusion more complete. 80

The annular space between the two sides 10—10 provides a compartment 17 in which is disposed a strand of electric lights 19 of the small Christmas tree variety connected in series for use on a standard 110 volt light 85 circuit. The strand preferably comprises eight lamp sockets 18 and electrical wiring 20. The wiring 20 is disposed about the periphery of the annular collar or sleeve 15 and may be suitably anchored thereto. The 90 free ends of the wiring 20 are connected to a conventional outlet plug 21.

The artificial or imitation holly wreath above described is adapted to be hung in the window or any other analogous place during 95 the Christmas season. When the lamps 19 are lit the entire wreath is illuminated. That is to say, the light passes through the transparent sides 10, lighting up the wreath or other ornamentation upon each of the card- 100

board or paper side layers 11. The celluloid coverings 12-12 provide the sides with a glossy finish, thus enhancing the appearance of the wreath.

5 In Figs. 3 and 4 I have illustrated a modification of my invention wherein the collar or sleeve 15' is preferably provided with a plurality of perforations or openings 25, there being one for each socket and lamp 19'.

10 In this form of the invention the wiring 20' is disposed on the inner periphery of the tubular sleeve or collar 15' rather than on its outer periphery, as is shown in Fig. 2. Furthermore, at each opening 25 the collar 15' 15 is provided with a laterally extending flange 26 through which the socket extends. This flange serves as a means for properly locating each socket and lamp, and also serves as a means for supporting the lamp and socket.

20 In this modification of the invention the sides 10'-10' are identical to the sides 10-10' of the preferred form of my invention. The only difference in structure resides in the connecting sleeve 15' which has been previously 25 described.

Now I desire it understood that, although I have illustrated and described in detail the preferred forms of my invention, as constituting a wreath, the invention is not to be thus limited, but may be embodied in any similar illuminated device except in so far as defined by the scope and spirit of the appended claims. As above indicated, and as will be understood by those skilled in the art, changes 35 in construction and arrangement of parts of my invention may be resorted to without departing from the field and scope of the same, and I intend to include all such variations, as fall within the scope of the appended 40 claims, in this application in which the preferred forms only of my invention are disclosed.

I claim:-

1. An imitation wreath comprising a pair 45 of annular sides having coaxial central openings, one of said sides being ornamented and translucent, a connection between the sides connecting them at their openings, and a strand of electric lights disposed about said 50 connection between said sides for illuminating said ornamented side.

2. An imitation wreath comprising a pair 55 of translucent sides, each of said sides being ornamented to simulate a wreath, a sleeve disposed at substantially the central portions of each of said sides for connecting the sides together, the peripheral edges of said sides being bent toward each other, and a strand of electric lights disposed about said sleeve in 60 the space separating said sides.

3. An imitation wreath comprising a pair 65 of transparent sides having coaxial openings, each of said sides being ornamented to simulate a wreath, a sleeve disposed between the sides for connecting them at their openings,

said sleeve being disposed substantially centrally with respect to the sides, the outer peripheral edges of the sides being bent toward each other, and a strand of electric lights disposed about said sleeve between said sides, 70 each of said sides comprising an ornamented card cut to simulate a wreath, and a celluloid covering glued to the card for giving the side a glossy finish.

4. In combination, a pair of side members, 75 a sleeve-like structure connecting the side members in spaced relation, and illuminating means carried by the sleeve structure and projecting outwardly beyond the same for illuminating the space between the side members.

5. In combination, in a device of the character described, a pair of side members having substantially aligned openings, one of said members being translucent and simulating a natural wreath, and a sleeve disposed between said members and connecting them at the openings thereof, said sleeve providing a support for illuminating means disposed between the side members for illuminating 80 said translucent side member.

In witness whereof, I hereunto subscribe my name this 18th day of March, A. D. 1927.

LOUISE GASTON.
